UNITED STATES PATENT OFFICE

2,561,424

HEAT TRANSFER ELEMENT

Benjamin Spieth, Racine, Wis., assignor to Modine Manufacturing Company, Racine, Wis., a corporation of Wisconsin

Application November 17, 1948, Serial No. 60,569

2 Claims. (Cl. 257—50)

1

This invention relates to a heating system and in particular, to a heat transfer element especially designed for use in a system known commercially as a "one pipe steam system."

A steam heating system, the type or design known as a one pipe system, is probably the least complicated and hence is more economical in installation. As the name implies, only one circuit of pipe from the boiler to the heat transfer element is required, that is, it is a one pipe system. In comparison the conventional system has two pipes, that is, two pipe circuits and hence is more costly of installation.

In the one pipe system steam flows from the boiler out to the heat transfer element, is condensed, and the condensate returns to the boiler through the same pipe. Consequently, steam is flowing in one direction in the pipe and the condensate water is flowing in the opposite direction. This condition, together with the fact that there is usually air in such a system, heretofore has resulted in erratic, faulty and inefficient performance.

The two pipe system usually gives more definite and efficient performance since the steam and condensate travel in the same direction, but such a system is more costly.

The invention has, among its objects, the production of a heat transfer element that will eliminate the above objections, which is very simple in construction, efficient in operation, and in which a single horizontally extending header member may be employed.

Another object of the invention is the production of such an element in which substantially all the elements may be in the form of stampings or the like and bonded in a single operation into an integral unit, whereby cost of manufacture may be reduced to a minimum.

Other objects and advantages will appear in the course of this specification and with said objects and advantages in view, this invention consists in the several novel features hereinafter fully set forth and more particularly defined in the appended claims.

The invention is clearly illustrated in the drawing accompanying this specification in which:

Fig. 1 is a plan, partly broken away and partly broken out, of a heat transfer element embodying a simple form of the present invention. And

Fig. 2 is a vertical longitudinal section taken on the line 2—2 of Fig. 1.

Referring to said drawing which is merely illustrative of one embodiment of the present invention, the reference character 5 designates a steam supply pipe and 6 designates the tubular wall of a steam inlet header connected to the pipe

2

by a chambered extension 7. In the form of the invention illustrated, the steam inlet header is of horizontal tubular form from which the extension 7 extends downward, and communicates with its interior through a port 8 in the tubular wall of the steam inlet header. Heads or end walls 6a bonded or otherwise secured to the tubular wall close the ends of the header.

A partition 9 welded or otherwise secured to the tubular wall of the header divides the latter into a steam inlet chamber 10 and an air and condensate chamber 11. From the steam inlet chamber 10 leads a substantially horizontally extending tube or several tubes 12 which are bonded or otherwise secured to the partition 9. Bonded or otherwise secured to the tubular wall of the header and leading from the air and condensate chamber 11, is a tube or tubes 13 of greater diameter than the tubes 12 and surrounding said tubes 12. The tubes 13 are of greater length than the tubes 12 and having their ends opposite the header, closed by closures 14 bonded or otherwise secured to the tubes 13. When the present heat transfer element is applied to a convection heater, fins or heat radiating plates 15 are strung along the tubes 13 and are bonded or otherwise secured thereto. Communicating with the air and condensate chamber 11 through a nipple 16 is a thermostatic air valve 17 having a discharge port 18 through which air is released from the heat transfer element, and extending down from the air and condensate chamber is a trap or water seal 19 which is bonded to or otherwise secured to the tubular wall of the header 6. The trap extends down into the extension 7 or it may be of a length to extend down into the steam supply pipe 5, if such a high head of water is required to direct the steam in its proper course. One leg 19a of the trap is somewhat shorter than the other leg.

The heat transfer element may be supported in a convection heater cabinet in any suitable manner. The supporting means here shown comprises a bracket 20 bonded or otherwise secured to the tubular wall of the header and having an upright web 20a bolted or otherwise secured to one end wall 21 of the convection heater cabinet. The closed ends of tubes 13 extend through a vertical web of a second bracket 22 and are bonded or otherwise secured thereto and said bracket 22 has an upright web 23 which is bolted or otherwise fastened to an end wall 24 of the convection heater cabinet.

The several parts of the heat transfer element with the exception of the thermostatic air valve are first assembled with their surfaces coated with bonding material, and the assembly is placed in

a suitable oven and heat of sufficient temperature is applied to the assembly to fuse the bonding material, so that when cooled an integral structure is produced.

In operation steam enters the extension 7 through the steam pipe 5 and flows through the port 8 into the steam inlet chamber 10. From the chamber 10 the steam enters the tube or tubes 12 and flows to their far ends forcing any air that may be in the tubes 12 ahead of it. Since the tubes 12 have little or no contact with the outer tubes 13, little or no condensation of steam will occur in the tubes 12.

As the steam leaves the outer ends of the tubes 12 and enters tubes 13 the outer tube walls, and the fins absorb heat and condensation of the steam occurs. The flow of steam, air and condensate between the tube walls is all in one and the same direction and toward the air and condensation chamber 11. In chamber 11 the air separates from the condensate and rises into thermostatic air valve 17 and is discharged through port 18.

The condensate drops down through chamber 11 and into the trap 19, where it overflows from the shorter leg back into the steam pipe 5 and drains back to the boiler. Thus the flow of the mixture of steam, air and water in the heat transfer element is always in the same direction, and satisfactory performance results.

When the steam is first turned on after a period of inoperation, the water in the short leg may be depressed with a corresponding rise of the water in the longer leg, providing the pressure head causing the circulation to be in the right direction.

Under somewhat unusual conditions, the pressure head may be insufficient to cause proper flow of the steam, air and condensate. In such cases the water trap may have longer relative length than shown, even extending below the nominal lower limit of chamber 11, and reaching down into the pipe 5.

I am aware that attempts have heretofore been made to employ a heating unit in a one pipe steam system, one example of which is the heating unit disclosed in the patent to W. W. Ehrlich, No. 2,056,263, dated October 6, 1936, but that unit employs a cumbersome cored casting in which the air and condensate are separated. Furthermore, a manifold is required to connect the tubes disclosed at different levels.

My heat transfer element does not require a core casting nor a manifold, as the parts may be constructed of light gauge material bonded together, and the steam conveyed from the steam inlet chamber, by a tube or tubes extending into tubes of larger diameter and discharging thereinto, where the steam condenses and flows back to an air and condensate chamber from which it discharges through a trap back into the steam supply pipe.

Having thus described my invention, it is obvious that various immaterial modifications may be made in the same without departing from the spirit of my invention; hence, I do not wish to be understood as limiting myself to the exact form, construction, arrangement and combination of parts herein shown and described or uses mentioned.

What I claim as new and desire to secure by Letters Patent is:

1. A heat transfer element for a single pipe steam system, comprising in combination a header

member, a partition wall positioned in said member and dividing the same into a steam inlet chamber and an adjacent air and condensate chamber, an extension positioned below said header member and arranged to be connected to a steam pipe, an air venting valve operatively communicating with said air and condensate chamber, a substantially horizontal steam tube connected to said partition wall and communicating with said steam chamber, said steam tube extending through said condensate chamber, a tube of greater diameter than the steam tube and surrounding the same, said tube of greater diameter being connected to the outer wall of said air and condensate chamber and communicating with the latter, said tube being closed at its end opposite thereto, fins strung along the tube of greater diameter and secured thereto, and a tubular trap member extending downwardly from said header into said extension, with the upper end of said trap member communicating with the air and condensate chamber, the lower end of said trap member having an outlet opening communicating with said extension, said opening being positioned above the bottom of the trap member with the portion of the latter below said opening being operative to collect condensate therein in opposing the entrance of steam through said trap member into the air and condensate chamber.

2. A heat transfer element for a single pipe steam system, comprising in combination a header having a partition therein dividing the same into a steam inlet chamber and an air and condensate chamber, an air venting valve operatively communicating with said last mentioned chamber, both chambers being of substantially the same length as the header, a substantially horizontal steam tube connected to said partition and communicating with the steam inlet chamber, said steam tube extending through the condensate chamber, a tube of larger diameter than the first mentioned tube surrounding the same and connected to an outer wall of and communicating with said air and condensate chamber, said tube of greater diameter being closed at its end opposite the header, fins strung along the outer tube and secured thereto, a downwardly extending extension carried by said header communicating with said inlet chamber and adapted to be connected to a steam supply pipe, and a tubular trap member extending down from the header into said extension and communicating with the air and condensate chamber, the free end of said trap member having a U-bend therein, with the free open end of said trap member being positioned above said bend and communicating with the extension interior, said bend being operative to collect condensate therein to oppose the passage of steam through said trap member into the condensate chamber.

BENJAMIN SPIETH.
